DESIGN FOR A THREE ROOM CANVAS COTTAGE

Jolly L. Morris and Robert N. Morris,
McDonald, Pa.

Application July 12, 1934, Serial No. 52,564

Term of patent 14 years

To all whom it may concern:

Be it known that we, Jolly L. Morris and Robert N. Morris, citizens of the United States, residing at McDonald, in the county of Washington and State of Pennsylvania, have invented a new, original, and ornamental Design for a Three Room Canvas Cottage, of which the following is a specification, reference being had to the accompanying drawing, forming part thereof.

Figure 1 is a perspective view of our cottage in assembled position on a scale slightly enlarged over the remaining figures,

and

In Figures 3, 4, 5, and 6 the guy wires are not shown.

We claim:
The ornamental design for a three room canvas cottage, as shown and described.

JOLLY L. MORRIS.
ROBERT N. MORRIS.
